MACHINE FOR RAISING AREAS ON
PRINTING PLATESIsidor Tornberg, Plainfield, N. J., assignor to
Wood Newspaper Machinery Corporation, New
York, N. Y., a corporation of New YorkApplication May 12, 1931, Serial No. 536,720
Renewed April 4, 1934

6 Claims. (Cl. 153—48)

In the manufacture of printing plates it is very difficult to provide a plate with a means that will emphasize certain characters or parts of the printed page without considerable manual and time-consuming work on the part of the operator. At the present time, where it is desired to bring out, more fully than a printing plate otherwise would, some feature of the printing plate, this is accomplished by an operation called bumping.

10 An elaborate but crude set of tools is used whereby those portions of the plate to be emphasized are peened up slightly above the type level.

The object of this invention is to provide a machine in which this bumping or peening may 15 be done in a simple, easy and uniform manner without involving so much chance of error and with the saving of a material amount of time; also to provide a machine in which a cylinder is mounted in such a way that it can be turned at 20 will to bring any part of its surface to the top, said cylinder carrying the printing plate to be operated upon; to provide the cylinder with means operated from within for performing the bumping operation and to provide means located on the 25 outside of the plate and always in alignment with the bumping means inside for supporting the printing surface of the plate and cushioning and confining the bumping action.

Other objects and advantages of the invention 30 will appear hereinafter.

Reference is to be had to the accompanying drawings, in which

Fig. 1 is a longitudinal diametrical cross section of a machine comprising a preferred embodiment 35 of this invention, showing it in position to act on a plate;

Fig. 2 is an end view of the same;

Fig. 3 is an enlarged section, like a part of Fig. 1, showing the anvil in position, and

40 Fig. 4 is a similar view showing the operation of the bumping device pneumatically.

For the above mentioned purposes, a frame 10 is provided, having bearings in which are supported the hubs 11 of a cylinder 12. This cylinder 45 is free to be turned by hand in the bearings to bring any part of the cylinder to the top. The cylinder carries a detachable end 13 on which one of the hubs 11 is fixed. On the cylinder is mounted one or more stationary beveled clamps 14 for one 50 end of the printing plate P and at the other end is a movable clamp 15 for the other end of the plate. The clamp 15 is operated by a screw 16 and hand wheel 17 having its bearing in the end plate 13.

55 The end plate 13 carries a projection 18 on

which is pivoted a handle 19 by means of a pin 20. This handle or pin carries a toe 21 fitting in notches 22 provided in the top of the frame 10. This positioning device is provided to make the operation easier by holding the cylinder in a definite position circumferentially after being placed there.

It will be understood that the printing plate P is preferably semi-cylindrical, such as is commonly used in the newspaper printing art, but 65 the principle can be applied to other types of plates.

In the hubs 11 of the cylinder 12 is journaled a shaft 23, this shaft being slidably mounted in these bearings so that it can be moved back and forth and turned circumferentially. On the shaft is pinned a motor base 24 having a counterweight 25 for holding the motor 26, carried on top of the base 24, always at the highest point wherever the shaft is turned. At the end of the shaft 23 is a 70 locating and operating arm 27, the end of which is always located over some part of the printing plate. The end is provided with a backing plug or anvil 28 movably mounted. This anvil carries, secured to it, a semi-resilient washer 29 which 75 may be of cork, leather or a rubber composition that will not be too soft. The anvil 24 is carried on a radially slidable stud 30 having pinned to the upper end a handle 31. A spring 32 is provided for holding these parts up in the position shown in Fig. 1. The handle may be pressed down to bring the washer 29 into contact with the plate P where it will steady the plate against blows imparted to it and also will localize the peening action to the section directly under this 80 washer.

It will be obvious that by turning the locating arm 27 and moving it back and forth, this anvil can be located over any desired part of the printing plate to provide for the projection of that 85 part from within against the washer 29. This washer will yield enough to allow the plate to push up slightly but being backed up by a metal part and having only a semi-resilient character it will not yield materially or allow the raising 90 or bumping effect to spread. The peening action is intended only for bringing the desired printing surface out sharply in the print and not preventing a good print being made from the rest of the plate.

As the handle 31 is forced down a contact ring 33 is brought into a position to connect two brushes 34 with each other electrically. These brushes are connected by wires 35 with the motor 26 and start it up.

The motor carries on its main shaft a crank 37 to which is pivotally attached a link 38 by means of a stud 39 on the crank. The link extends upwardly and its upper end is pivotally attached to a cross head 40. This cross head is mounted to be free to slide up and down. A horn 41 is carried by the motor base and preferably is integral therewith. A hammer head 42 is slidably mounted in the cross head 40. It is limited in its endwise motion therein by a pin 43 operating in a slot 44 in the cross head. A spring 45 above the horn 41 normally holds the head 42 in its outermost position and provides a yielding connection in the motion. It will be seen that the rotation of the shaft of the motor causes, through this chain of connections, the striker or hammer 42 to deliver blows upwardly.

The part of the cylinder over which the plate P is located is provided with a series of small radial plungers 46 and in fact the surface of the cylinder within this area is literally covered with these plungers located as near together as possible for acting against the bottom side of the printing plate which is clamped upon it. Each plunger 46 is arranged radially and provided with a spring 47 to return it to a point at a distance from the plate and a collar 48 against which the spring acts. These plungers otherwise are free to move in accordance with the action of the hammer 42.

The result of the operation will be obvious from an inspection of Fig. 3. Of course, it will be understood that the axis of the cross head 40 is always in alignment with the axis of the slidable stud 30 and that, however the locating arm is placed, the motor moves around with it either longitudinally or circumferentially and these two parts are always in alignment.

It will be seen that the operator, by grasping the handle 31 may move the locating device circumferentially and longitudinally along the plate. He has the anvil 28 and washer 29 right before him so that he can place them against the surface to be projected or bumped and is sure that the operation will take place in exactly the right spot. The action of pushing down the handle 31 operates the motor as long as this handle is left down and one or more blows may be imparted to the plate to push its surface outwardly.

Referring to the handle 19 and notches 22, it will be seen from Fig. 2 that three of these notches are shown. If the operator is working in the central portion of the plate, the cylinder is positioned as shown therein. When he has to work on the left hand part of the plate, the handle 19 is disengaged from the notch and the cylinder moved to the right and the projection 21 engaged in the right hand notch. This brings the left hand part of the plate on the top where he can see it to work on.

Fig. 4 simply shows the same mechanism with a pneumatic hammer 50 supplied with air, or any fluid under pressure, through a pipe 51 and operating substantially in the same way. No further details of this construction are shown as the usual elements employed in a pneumatic hammer are also employed here.

Although I have illustrated and described only two forms of the invention I am aware of the fact that other modifications can be made therein by any person skilled in the art without departing from the scope of the invention as expressed in the claims. Therefore I do not wish to be limited in this respect but what I do claim

is:—

1. In a device for raising part of the surface of a stereotype printing plate, the combination of a cylinder mounted to be freely rotatable, means on the cylinder for holding a printing plate thereon, the surface of the cylinder under the printing plate being provided throughout with a series of small plungers, a shaft on the cylinder free to rotate independently of the cylinder, a hammer head radially and reciprocably carried by said shaft inside the cylinder, an arm fixed to said shaft and projecting over the outside of the printing plate, and an anvil carried by said arm in radial alignment with said hammer head.

2. In a device for raising portions of the printing surface of a printing plate, the combination of a cylinder, means on the cylinder for supporting a printing plate to be operated upon, the entire surface of the cylinder under the printing plate being provided with a series of small radial plungers, a shaft passing into the cylinder axially and free to turn with respect thereto, an arm on the shaft extending over the plate, an anvil on the arm having a semi-resilient surface adapted to be held against the part of the type surface to be raised, a hammer movable radially in the cylinder and in alignment with said anvil, and means for reciprocating said hammer to engage the plunger that is in line with the hammer and anvil to force the plate outwardly against the anvil throughout the area of the plunger.

3. In a machine for raising an area of a stereotype printing plate, the combination with a cylinder having means for supporting a curved stereotype plate, radial plungers carried by the cylinder under the plate, a shaft extending through the cylinder and rotatable and slidable therein, a frame on the shaft in the cylinder comprising a counterweight, a motor on the frame, means operated by the motor for engaging one of the plungers and forcing the plate out thereby, and means on the outside of the cylinder for engaging the plate to receive the blows.

4. In a machine for projecting the area of printing surfaces, the combination of a cylinder mounted to be turned freely in its bearings, means adapted to be set in different positions for holding the cylinder against turning, means on the cylinder for supporting a printing plate to be operated upon, the area under the plate being filled with a series of radial plungers adapted to engage the rear surface of the plate, a shaft extending into the cylinder, movable axially and rotatable, by hand, independently of the cylinder, an anvil having a semi-resilient surface at the inner end adapted to engage the type surface, a motor fixed on said shaft inside the cylinder, electric connections for starting the motor, and means operated by the motor for delivering blows on the rear end of one of said plungers which is in radial alignment with the anvil.

5. In a machine for projecting the area of printing surfaces, the combination of a cylinder, means on the cylinder for supporting a printing plate to be operated upon, the area under the plate being filled with a series of radial plungers adapted to engage the rear surface of the plate, a shaft extending into the cylinder, movable axially and rotatable, by hand, independently of the cylinder, an arm on the shaft outside, a radially slidable stud on the arm, an anvil having a semi-resilient surface at the inner end adapted to engage the type surface, a handle connected with the stud for moving the anvil into engagement with the type surface, an electric contact

arranged to be closed by the movement of said stud, a motor fixed on said shaft inside the cylinder, whereby the motor will be started and kept going as long as the stud is depressed, and means 5 operated by the motor for delivering blows on the rear end of one of said plungers which is in radial alignment with the anvil.

6. In a device for raising part of the surface of a stereotype printing plate, the combination 10 of a support mounted to be freely moved, means

on the support for holding a printing plate thereon, the surface of the support under the printing plate being provided throughout with a series of small plungers, a hammer head reciprocably carried inside the cylinder, an arm connected with said hammer head and projecting over the outside of the printing plate, and an anvil carried by said arm always in alignment with said hammer head.
